US00D614757S

(12) United States Design Patent
Noble

(10) Patent No.: **US D614,757 S**
(45) Date of Patent: **** Apr. 27, 2010**

(54) FAN

(75) Inventor: **Ernest John Noble**, Selangor (MY)

(73) Assignee: **HAIKU DESIGN Sdn Bhd (MY)**

(**) Term: **14 Years**

(21) Appl. No.: **29/334,434**

(22) Filed: **Mar. 26, 2009**

(30) Foreign Application Priority Data

Sep. 30, 2008 (SG) D2008/951/E

(51) LOC (9) Cl. **23-04**

(52) U.S. Cl. **D23/377**

(58) Field of Classification Search D23/377,
D23/379, 385, 411, 413; 416/5; D26/51,
D26/72, 81-86, 88

See application file for complete search history.

CERTIFICATE OF CORRECTION

PATENT NO. : Des. 614,757 S
APPLICATION NO. : 29/334434
DATED : April 27, 2010
INVENTOR(S) : Ernest John Noble

Page 1 of 7

It is certified that error appears in the above-identified patent and that said Letters Patent is hereby corrected as shown below:

Title page should be deleted and substitute therefor the attached title page.

Drawings:

Delete the drawings 1-5 and substitute the drawing sheets consisting of Figs. 1-5 as shown on the attached pages.

Signed and Sealed this

Thirteenth Day of July, 2010

David J. Kappos
Director of the United States Patent and Trademark Office
